UNITED STATES PATENT OFFICE.

WILLIAM M. BRUCE, JR., OF SPRINGFIELD, OHIO, ASSIGNOR TO THE UNITED TELEGRAPH & CABLE COMPANY, OF SPRINGFIELD, OHIO, A CORPORATION OF OHIO.

TELEGRAPH SYSTEM.

1,145,229.

Specification of Letters Patent.

Patented July 6, 1915.

Application filed November 7, 1913. Serial No. 799,812.

To all whom it may concern:

Be it known that I, WILLIAM M. BRUCE, Jr., a citizen of the United States, residing at Springfield, in the county of Clark and 5 State of Ohio, have invented certain new and useful Improvements in Telegraph Systems, of which the following is a specification.

My invention relates to improvements in 10 telegraphy and particularly relates to a system of telegraphing with alternating currents.

In the accompanying drawings, Figure 1 is a diagram showing a system embodying 15 my invention. Fig. 2 is a diagram showing a modification of the same.

Like parts are represented by similar characters of reference in the several views.

In the said drawings, *a* represents an alternating current generator, one pole of 20 which is grounded at *g* and the other connected by wire or conductor *b* to contact *b'*.

c is an ordinary telegraph key connected by wire *d* to condenser *e*; thence by wire *e'* 25 to relay *f* and wire *f'* to a cable or conductor which leads to another station.

The relay *f* is a delicate relay and is so wound that when the key *c* is depressed, the 30 relay will respond to the alternations from the generator *a* as well as to the make and break impulses which may be made by the key *c*.

The relay *f* is provided with an armature spring *h* adapted to engage the forward contact *h'* which is connected through wire *h''* 35 to an electro-magnet *h³* of a receiving and recording device *R*; thence by wire *h⁴* to battery *B* and wire *h⁵* to the armature *h*.

This electro-magnet *h³* is also so constructed 40 that it will respond to the vibrations of the armature *h*. This electro-magnet *h³* is arranged to operate a recording pen *p* by vibrating the same to or from a moving tape *t*. The tape *t* is arranged to be moved by a suitable mechanism such as a clock circuit 45 gearing as indicated at *j*, *j'*, *j''*, so as to move at a uniform speed when the mechanism is started so that the pen *p*, as it is vibrated to and from the tape, will produce a series of impressions thereon.

50 In order to control the movement of the tape from the relay *f*, I provide a branch circuit leading from the wire *h²* by wire *h⁶* to a slow or sluggish magnet *k*; thence by wire *h⁷* to wire *h⁴* so that the vibrations of 55 the relay *f* will energize the magnet *k*.

This magnet *k*, however, is made slow or sluggish by the use of a copper jacket or otherwise, so that so long as the relay *f* is operated in a fairly rapid manner, the magnet *k* will remain energized and only become 60 deenergized after the relay *f* has ceased to operate for a definite interval of time. This magnet *k* is, by means of an armature *k'* and a pawl-lever *k''*, adapted to release the 65 clock mechanism *j* to cause the tape to move.

If the tape, moving at a uniform speed, is impressed by the pen *p* at each movement of the armature *h* in response to the alternations of current and these alternations are sufficiently rapid, the result would be a series 70 of small dots. If the making of these dots is interrupted by interrupting the current, a space would occur and these interruptions, together with the dots, would make long and short groups or a series of dots representing the ordinary Morse alphabet. In order, however, that the alphabet may be made in the usual dots and dashes of an ordinary recording instrument, I arrange the travel of the tape in a given ratio to the 75 alternations of the current and I also make the pen *p* of a sufficient length in the direction of the travel of the tape so that the result will be a series of short and long dashes instead of groups of small dots. 85

For illustration in using an ordinary sixteen-cycle current, the armature *h* will vibrate thirty-two times per second which will cause the pen *p* to vibrate a similar number of times. In such case, I arrange the tape to 90 travel at the rate of an inch per second which would make, by the alternations of the current, thirty-two dots to each inch of tape which would be separated by a similar number of spaces, a dot and space occupying a thirty-second of an inch. Now, in order that these dots may make a continuous line in the event that the armature *h* vibrates in response to the alternations of the current only, I make the end of the pen 95 *p* of a sufficient length in the direction of the travel of the tape so that at each impression, the back edge of the pen would engage the back of the previous impression and thus make a continuous line. Then, by 100 manipulating the key *c* in accordance with the well-known Morse or other alphabet, the result would be a series of short and long dashes separated by the usual spaces in exact accordance with the alphabet adopted. 110

By using the slow magnet k , which will be energized whenever the circuit is closed at the armature h but shall remain energized so long as current impulses in fairly rapid succession occur, means are provided by which the tape is automatically started as soon as the circuit is closed at the key c and continues to move until the circuit has been broken for a certain definite length of time, 10 when the magnet k will be deenergized and allow the pawl lever h^2 to engage the tape-operating mechanism and stop the same. In Fig. 2, I have shown a modification in which the relay f , through its armature h , operates 15 an electro-magnet h^3 which controls a vibrating lever l operating in a toothed wheel m which in turn vibrates a lever n carrying a pen p which operates on a tape t , in a manner already described. The toothed wheel m 20 may be operated by any suitable mechanism such as a clock mechanism or otherwise, the toothed lever l being formed at the top with arms l' and l'' to produce an escapement device similar to an ordinary clock mechanism. The tape t will be arranged to move, 25 as before described, in connection with the pen p , and the vibrations of the lever l , in response to the relay f , will cause a succession of dots and dashes and spaces on the 30 tape t , as before described. It is obvious that the same arrangement of the slow magnet for stopping and starting the operation of the tape mechanism may be employed if desired.

35 An interrupted current having interruptions of substantially the same frequency as the frequency of an alternating current may be used instead of an alternating current under some circumstances with fairly good 40 results, and, where an alternating current is described, it is intended to cover either alternating or interrupted current.

Having thus described my invention, I claim:

45 1. In a telegraph system having a relay in circuit with an alternating current and adapted to respond to the alternations as well as the interruptions of said current, a local circuit controlled by said relay and an 50 electro-magnet operating in response to said relay, a recording device controlled by said electro-magnet embodying a tape whose movement is arranged in ratio to the alternations of said current, and a marking device adapted to vibrate in response to the 55 alternations and produce a continuous mark on said tape and by interruptions in said

current make long and short dashes and spaces, as described.

2. In a telegraph system, a relay in circuit with an alternating current supply, a circuit breaker and condenser, said relay being adapted to be operated by the alternations of said current as well as the interruptions therein, a local circuit including a 60 magnet controlled by said relay, a recording device operated by said electro-magnet embodying a tape, means for moving said tape and a slow magnet also operated by said relay adapted to be energized and remain 65 energized so long as said relay is operated, and means controlled by said slow magnet to stop and start said tape, as specified.

3. In a telegraph system for alternating currents embodying a relay which responds 70 to the alternations as well as to the interruptions of said current, a local circuit having an electro-magnet controlled by said relay, a recording device operated in part 75 by said electro-magnet and in part by other operating mechanism and a magnet also in circuit with said relay adapted to be energized and remain energized while said relay is operating in fairly rapid succession, and means controlled by said magnet for starting 80 and stopping said mechanism in said recording device.

4. In a telegraph system, a source of alternating current supply, a current interrupter and a relay in circuit with said current supply, said relay being constructed to respond to the alternations of current as well as to interruptions therein, a recording device controlled by said relay consisting in 90 part of a marking instrument adapted to 95 vibrate in response to the alternations and in part of a moving surface against which said marking device operates, the movement of said surface and the length of the marking instrument being so proportioned that 100 in the ordinary vibrations from the alternations of the current the marking instrument will close the spaces between the successive impressions thus making a continuous line and leave spaces between the said impressions in response to the interruptions of the 105 current.

In testimony whereof, I have hereunto set my hand this 30th day of October, 1913.

WILLIAM M. BRUCE, JR.
